ATTORNEY

UNITED STATES PATENT OFFICE.

MAX HORN, OF TOWER CITY, PENNSYLVANIA.

CLOCK.

Specification of Letters Patent. Patented June 20, 1922.

1,420,549.

Application filed November 12, 1921. Serial No. 514,619.

To all whom it may concern:

Be it known that I, MAX HORN, a citizen of the United States, residing at Tower City, in the county of Schuylkill and State 5 of Pennsylvania, have invented new and useful Improvements in Clocks, of which the following is a specification.

This invention relates to improvements in 10 clocks and has for an object the provision of an improved gravity operated clock, wherein the use of springs is dispensed with, the construction being such as to materially reduce the parts and simplify the operation of the clock.

15 Another object of the invention is the provision of a clock of the above character, having novel means for setting the hands.

20 A further object is the provision of a simple, novel and improved means for securing the hands to the clock.

With the above and other objects in view, the invention further includes the following novel features and details of construction, to be hereinafter more fully described, illustrated in the accompanying drawings and pointed out in the appended 25 claim.

In the drawings:—

Figure 1 is a front elevation of a clock 30 constructed in accordance with the invention.

Figure 2 is a side view of the same.

Figure 3 is an enlarged rear elevation 35 illustrating a portion of the clock mechanism.

Figure 4 is an enlarged side elevation of the clock mechanism with the casing broken away and shown in section.

Figure 5 is a detail rear elevation of a 40 portion of the clock mechanism.

Figure 6 is a front view of the clock mechanism removed from the casing.

Figure 7 is a detail view illustrating the 45 means for locking the operating gear to its shaft.

Figure 8 is an enlarged sectional view illustrating the manner of securing the hands in position.

Referring in detail to the drawings, 50 wherein like characters of reference denote corresponding parts, the reference character 10 indicates the base, which may be of any desired ornamental configuration and which has rising therefrom spaced standards 11, the latter being connected at their 55 ends by means of a bar 12. This bar is

preferably arch shaped as shown, so as to add to the appearance of the clock which is indicated generally at 13 and whose casing 14 is shaped to be received within the 60 arch 12. The clock 13 is capable of vertical movement, so that its casing 14 has extending from opposite sides thereof arms 15, which have openings in their outer ends for the reception of the standards 11, so as to 65 provide guides for the clock during its movement.

Also rising from the base 10 intermediate the standards 11 is a rack bar 16, whose upper end is secured to the arch 12. This 70 rack bar 16 passes through aligned openings 17 provided in the casing 14, so that the clock may be freely movable both on the standards 11 and the rack bar 16. Located within the casing 14 is a weight 18, 75 which is also provided with an opening for the passage of the rack bar 16, the said weight being designed to increase the weight of the clock mechanism, so that the latter will operate in a manner hereinafter 80 described to impart proper movement to the clock hands.

The clock mechanism, which is of a simple and efficient character, includes a pinion 19, which is fast upon a shaft 20. This shaft 85 is mounted in suitable bearings provided in arms 21, which are carried by a plate 22 and which form part of substantially L-shaped brackets carried by said plate, the said brackets having their ends opposite the 90 plates connected together, to provide a rigid mounting for the shaft 20. Loosely mounted on the shaft 20 is a gear 23, and this gear carries a pivotally mounted spring actuated dog 24, which engages the teeth of 95 a ratchet wheel 25, fast upon the shaft 20. The gear 23 will thus be locked to the shaft 20 when the latter is rotating in one direction but will permit of independent rotation of the shaft, when the latter is rotating in 100 a reverse direction. The gear 23 engages a pinion 26, which is mounted upon a shaft 27, while also mounted upon this shaft is a pinion 28, which engages a gear 29. This last named gear engages a gear 30, which in 105 turn engages a pinion 31, while mounted upon the shaft of the pinion 31 is a gear 32. This last mentioned gear engages a pinion 33 which is fast upon a shaft with a gear 34 and the latter operates a pinion 35 for driving the escapement 36. The gear 30 is mounted on an arbor 37, upon which is 110

secured a pinion 38 and the latter engages a gear 39 and a shaft 40. Mounted upon the shaft 40 is a pinion 41, which engages a gear 42 on the inner end of a sleeve 43. This sleeve rotates upon a sleeve 44 which is mounted on the arbor 37. The inner end of the sleeve 44 carries a pinion 45, which is driven from a gear 46 upon the shaft 40 and acts to rotate the minute hand 47 which 10 is secured upon the outer end of the said sleeve 44. The hour hand 48, is secured upon the outer end of the sleeve 43 and is held in position upon said sleeve by the minute hand 47, the latter having a threaded 15 engagement with the outer end of the sleeve as shown at 49.

Engaging the gear 39 is a gear 50, which is adapted to be manually rotated to set the hands of the clock. For this purpose, there 20 is provided a pinion 51 which is secured upon the inner end of a shaft 52, the latter being mounted for sliding movement in a bearing 53 and normally forced away from the gear 50 by means of a spring 54, which 25 bears against the bearing 53 and a collar 55 upon the shaft 52. The outer end of this shaft is provided with a knob 56, by means of which it may be operated. When it is desired to set the hands of the clock, the 30 shaft 53 is moved inward until the pinion 51 engages the gear 50, whereupon the sleeves 43 and 44 of the hands 47 and 48 may be rotated through the gearing just described.

35 In the operation of the clock, the weight of the latter will cause the clock to slowly descend, guided by the standards 11. This downward movement will impart rotation to the mechanism through the rack 16 and 40 pinion 19, the gear 23 which controls the operation of the clock mechanism being locked to the shaft 20 through the dog 24

and ratchet wheel 25. After the clock has reached the limit of its downward movement, or at any point during this movement, 45 the said clock may be manually moved upward. During this upward movement, the clock mechanism is released from the rack 16, as the gear 23 is free on the shaft 20 at this time. 50

The invention is susceptible of various changes in its form, proportions and minor details of construction and the right is herein reserved to make such changes as properly fall within the scope of the ap- 55 pended claim.

Having described the invention what is claimed is:—

A clock embodying a base, a pair of spaced parallel guide standards rising from 60 the base, means connecting the upper ends of the standards, a clock casing, arms extending from the opposite sides of the casing and slidingly engaging the parallel standards, a clock mechanism within the casing, 65 a weight located within the casing, a rack bar extending upward from the base between the standards and through the clock and weight and connected to the standard connecting means, substantially L-shaped 70 brackets mounted within the clock case and having one of their ends secured to the frame of the clock mechanism and their opposite ends connected together, a shaft having one end mounted in one of the brackets, 75 a pinion secured upon the shaft and engaging the teeth of the rack bar, a gear loose upon the shaft and operatively connected to the clock mechanism and means whereby the gear will be locked to the shaft when the latter is rotated in one direction only.

In testimony whereof I affix my signature.

MAX HORN.
